CORKSCREW

Henry G. Thompson, East Cleveland, Ohio

Original application May 2, 1931, Serial No. 534,593. Divided and this application September 19, 1933, Serial No. 690,153

7 Claims. (Cl. 65—48)

This invention is a division of my copending application, Serial No. 534,593, filed May 2nd, 1931, issued as Patent No. 1,930,492 of Oct. 17, 1933. The present invention relates to a combined bottle cork-screw and support therefor. A primary object of the invention is to provide a simple and efficient device of this character, which may be mounted on a wall or other suitable supporting surface, and which device may 10 be conveniently used for withdrawing corks.

A further object of the invention is to provide a combination cork screw and support therefor having a minimum number of parts, which parts may be very simple in construction, may be 15 economically manufactured and easily assembled, and will result in a very durable structure.

Pocket or portable cork-screws have well recognized disadvantages, among which may be 20 mentioned that they are easily misplaced and thus are frequently not available at the place desired, and their use is sometimes difficult and sometimes breaks up the cork, resulting in chips 25 passing into the contents of the bottle, while at other times the cork is extracted so vigorously as to spill the contents. To avoid these difficulties attached cork extracting devices have 30 been used, but they have usually comprised a number of cooperating parts and have been comparatively expensive to manufacture.

The specific object of my invention then is to provide a cork screw and support therefor, which may be permanently fastened to the walls of a building or room and which may be manufactured so cheaply that it can be retailed profitably at a very low price. Notwithstanding 35 the low cost, my cork screw, when once installed, is very effective in operation and durable in service.

In carrying out the above objects, the invention is susceptible of a wide range of modifications, without departing from the spirit or sacrificing any of the advantages of the claimed invention; there being shown in the drawing for 40 illustrative purposes a preferred and practical form in which Fig. 1 is a perspective view of my cork screw and its support, showing a bottle and cork; Fig. 2 is a plan view of my invention; Fig. 45 3 is a side elevation; Figs. 4 and 5 are cross-sections taken on the lines 4—4 and 5—5 respectively of Fig. 2; Fig. 5 is a plan view and Fig. 6 is a cross-sectional view taken on the lines 6—6 of Fig. 3.

Referring in detail to the drawing, 10 indicates a metal stamping formed with two mount-

ing plates or wings 11, said plates being adapted to be secured to any wall or suitable surface by any suitable securing members, such as screws 12. The metal between these wings or plates is stamped outwardly to form triangular shaped side walls 15 and 16, which extend outwardly at right angles from the mounting plates and terminate in an arcuate bridge or covering wall 17. The side walls 15 and 16, together with the bridge or covering wall 17, form a U shaped 10 guard 18, which extends downwardly and outwardly from the top of the wings 11. The guard 18 is open at its base. The opening at the rear of the guard is covered, when the device is in use, by the wall or other surface to which the device is secured. Adjacent its upper edge the covering wall 17 is provided with two slits 19 and 20. The metal between these slits is forced 15 downwardly, out of the plane of the covering wall, and stretched somewhat to form an arcuate 20 hanger 21, which extends within the recess formed by the guard 18.

A cork screw 22 extends into the recess formed by the guard 18 and has its upper end formed 25 into a ring or loop 23 which embraces the hanger 21. There is sufficient play or looseness between the corkscrew 22 and the hanger 21 to permit the corkscrew to pivot freely on the hanger between the side walls 15 and 16 of the guard 18, as well as between the covering wall 30 of the guard and the surface to which the device is secured. The covering wall 17 of the guard 18 extends downwardly some distance from the hanger 21 and is bent over at its lower edge 35 to form a lip 25, which, together with the surface to which the device is secured, and the side walls 15 and 16 of the guard, limit the angular movement. As the device is normally secured to a substantially vertically extending wall or surface it results, from the construction of the 40 guard, that when the cork is being withdrawn from a bottle, such bottle must be in a substantially vertical position. In the specified form shown in the drawing, I have limited the tilting of the bottle to approximately thirty degrees from the vertical, as I find that such an angle eliminates, for practical purposes, the spilling of the contents of the bottle while removing the cork therefrom.

The U shaped guard 18 provides a structure 50 which is extremely rigid and which will withstand much abuse without becoming distorted. It will also be noted that the pivot 21, which supports the cork screw, is an integral part of the guard. In devices of this nature, which 55

have been in use in the past, pins were used as pivots. The pivot ends of such pins passed through the supporting structure and were flattened or riveted to the structure. In devices 5 of such a character, the rivets often, under the influence of a sudden shock, tore loose from the supporting structure, with the result that the contents of the bottle was spilled and damage to rugs, furniture, etc. was done. My improved 10 structure eliminates such possibilities and thereby prevents such resultant damage. It will likewise be noted that the recess between the side walls 15 and 16 of the guard is considerably greater than the width of the cork screw. 15 Likewise, the pivot 21 is arcuately shaped to permit the cork screw to freely rock in a plane parallel with the pivot, that is, transversely of the recess formed by the guard 19. This transverse rocking or pivoting movement is of greater 20 advantage, as it is difficult to use such a device and maintain the direction of the pull normal to a horizontal line extending through the pivot. My improved device is so constructed that the 25 cork screw may freely rock to compensate for such irregularities in the direction of the force applied and hence lessens the strains on the device and practically eliminates the bending of the cork screw.

Another feature of my invention is the fact 30 that the design has no sharp projecting points, which anyone would ordinarily come in contact with. The cork screw being freely pivoted within the casing, always hangs when not in use, flat to the supporting surface. The cork screw 35 is also so made and hung that the point always lies flat against the supporting surface, so that there is no possibility of tearing clothing or scratching one's hands.

Thus, it will be seen that I have disclosed 40 a very simple cork screw and support therefor, or which can be made very simply and economically and yet one which is rigid, durable and which will readily withstand excessive strains. The support and pivot for the 45 cork screw are a one-piece metal stamping, which can be readily formed by one operation. Thus I have provided a support or hanger on which ordinary type cork screw is pivoted, which, together with the cork screw, consists of 50 only two pieces, and which device is readily attached to a wall or similar surface.

I claim:

1. In a cork extracting device, the combination 55 of a support, comprising two base portions lying in the same plane, two portions extending outwardly from the inner edges of the base portions, and a portion connecting the outwardly extending portions, and a corkscrew having a shank extending into the space be-

tween the outwardly projecting portions of the support and secured to said support.

2. The combination of a sheet metal support, having a base for attachment to a surface, spaced-apart walls extending from said base, an arcuate bridge wall connecting said side walls and having a narrow strip thereof depressed downwardly of the plane of the bridge, and a cork screw pivotally mounted on said strip and housed between said walls. 5

3. The combination of a base plate adapted to be secured to a flat surface, said base plate having a U shaped forwardly projecting portion closed at its upper and outwardly facing surfaces by the curved wall of the U, said U shaped portion being open at its base, and having a portion of the curved wall of the U depressed to form a pivot, and a cork screw extending between the side walls of the U and loosely mounted on said pivot and extending 20 below the lowermost extremity of the U shaped portion of the plate. 10

4. The combination of a base plate adapted to be secured to a flat surface, said base plate having a hollow forwardly projecting portion comprising two side walls and a top connecting wall, a member bent in from the top connecting wall adjacent the top of the base plate, and a cork screw pivotally mounted upon said member, whereby the cork screw is adapted to lie adjacent the base plate and is protected by the forwardly projecting portion. 25

5. The combination of a support made of a single integral sheet metal member having two base portions lying in the same plane, two 30 parallel outwardly extending portions leading from the inner edges of the base portions and a top portion connecting the outwardly extending portions, and a corkscrew pivotally carried by the support having its shank occupying the 35 space between the outwardly extending portions and below the top portions. 40

6. The combination of a support having a base for attachment to a surface, spaced-apart walls extending outwardly from the base, a top member integral with and connecting said walls, the lower portion of said walls being formed to present downwardly facing jaws and a corkscrew having a shank extending between said walls and pivotally connected thereto. 45

7. The combination of a support having a base for attachment to a surface, spaced-apart walls extending outwardly from the base, an arcuate top across said walls, a portion of said top pressed below the rest of said top in the form 50 of a strap and a cork screw pivotally carried by said strap. 55

HENRY G. THOMPSON.
